Attorneys

UNITED STATES PATENT OFFICE.

MARIE SWOPE, OF BELLEFONTE, PENNSYLVANIA.

INK PENCIL.

Application filed February 16, 1925. Serial No. 9,588.

This invention relates to fountain or ink pencils.

The object of the invention is to provide a pencil of this character which presents the appearance of an ever ready pencil and which is equipped with a wire writing point to which ink is fed whereby the marks made by the point are in ink.

Another object is to provide a pencil of this character which is extremely simple in construction and cheap to manufacture and which may be readily taken apart for cleaning or repairs.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a pencil constructed in accordance with this invention; and

Fig. 2 is a longitudinal section thereof.

In the embodiment illustrated 1 denotes the barrel or body portion of the pencil which may be constructed of any suitable material and has a comparatively small bore 2 extending throughout the length thereof. A cap-like section 3 is removably mounted on the rear end of the body 1 and has an eraser 4 at one end providing a chamber 5 for the housing of a finger grip 7 carried by a plunger rod 6, which reciprocates in the bore 2. This plunger rod 6 has a plunger 8 at its front end mounted fluid-tight in a sleeve 9 which is threaded on the front end of the body 1 and which forms an ink-reservoir 15. A tapered section 10 is threaded in the outer end of the sleeve 9 and has a small bore 11 extending longitudinally therethrough in which is mounted a wire 12 which projects at the front beyond said section and forms what may be termed the writing point 14. This wire 12 has its inner end extended into the ink reservoir 15

and is shown secured to one side wall of sleeve 9 as indicated at 13, so that the inner end of the wire will act as a stop for the plunger and at the same time, due to the connection between the wire and sleeve 9, 55 resiliency will be added to the feed wire to facilitate the flow of ink through the bore 11.

From the above description it will be obvious that this improved pencil is constructed of four sections the body section 1, the cap section 3, the writing section which includes sleeve 9 and the tapered extension 10. The plunger 8 carried by the rod 6 constitutes the filler for the ink reservoir 15 60 and when it is desired to fill said reservoir the top section 3 is removed and the plunger first moved forwardly and then drawn rearwardly whereby ink is sucked in through the bore 11 into the reservoir 15 and from which 65 it will flow slowly through the bore 11 and be fed to the writing point 14. It is understood that the ink is fed by capillary attraction along this wire 12 and the inner end of the wire as shown at 16 is bowed to 70 form a resilient connection of the wire with the sleeve 9.

I claim:—

In an ink pencil, an elongated body portion having a restricted bore extending therethrough, a rod extended through the bore and in close proximity to the wall thereof to guide the rod, a removable sleeve providing an ink barrel on one end of the body portion, a plunger on one end of the rod and operating in the sleeve to draw fluid into the sleeve, said plunger engaging the wall of the sleeve, a tapered section having a bore, removably secured at one end of the sleeve, a feed wire extending through the bore and tapered section and having one end secured to the sleeve, to cause fluid to be fed to the free end of the wire, and a finger grip on the opposite end of the rod for operating the rod. 80 85 90 95

In testimony that I claim the foregoing as my own, I have hereto affixed my signature.

MARIE SWOPE.
